UNITED STATES PATENT OFFICE

GEORGE A. STOFFEL, OF HUNTINGTON, INDIANA

CASTING BOX

Application filed March 29, 1930. Serial No. 440,024.

This invention relates broadly to casting boxes, and has more particular reference to the provision of a curved casting box for casting types for use on certain types of printing presses, especially those printing presses that are used for printing envelopes and the like.

A further object of this invention is to provide a curved casting box for making curved plates embodying a frame, a pair of complementary members comprising male and female members, mounted on the frame and adapted to be clamped together, the structure of the clamping members being such that a mat of the type which has been previously set in the regular way is inserted therein, together with a plate conformably fitting between said members and against the mat, said plate having an opening arranged therein through which one face of the mat will protrude when all the parts are so clamped.

A still further object of the invention is to provide a device of this character, which is simple in construction, thoroughly reliable, practical, and efficient in operation, and otherwise well adapted for the purpose desired.

In the drawings:

Figure 1 is a side elevation of the invention showing the parts prior to being clamped together.

Figure 2 is a top plan view thereof.

Figure 3 is a top plan view of the device showing the device in clamped relation.

Figure 4 is a vertical sectional view taken substantially on the line 4-4 of Figure 3.

Figure 5 is a perspective view of the apertured plate.

With reference more in detail to the drawings, it will be seen that my improved casting box for casting curved printing plates comprises a rectangular frame embodying longitudinal side members 5-5 connected by end members 6-6. Mounted in the frame, between the side members 5-5 is a pair of clamping members designated generally by the reference characters 7 and 8 respectively.

The members 7 and 8 are in the nature of clamping plates, the member 7 being the female clamping plate, and the member 8 being the male clamping plate. The female

clamping plate 7 at its lower end is bolted to the side members 5-5 of the frame preferably by two bolts 9 for securing the female member 7 on the frame obliquely or somewhat at an incline.

The male member 8 at its lower end is pivoted between the side members of the frame through the medium of a pivot bolt 10 passing through said side members and the lower end of said male member 8.

The female member 7 has the intermediate portion thereof designated by the reference character *a* concaved to provide a recess of substantially arcuate formation in cross section and a pair of side wings *b*-*b*. The member 8 is similarly formed, having the convex intermediate portion *a'* and the side wings *b'*. Thus it will be seen that the convex intermediate portion *a'* is adapted to be received in the intermediate concave portion *a* of the female member when the said members 7 and 8 are in clamped position.

As shown to advantage in Figure 1, the concaved portion *a* and the convex portion *a'* respectively terminate inwardly from the lower end of the respective members 7 and 8, the construction thus forming on the female member 7 at the lower end of the concaved recess a shoulder 11.

For disposition between the members 7 and 8, there is provided a plate 12 having a concaved intermediate portion 13 and side wings 14, the concaved portion 13 of the plate 12 being provided with a substantially rectangular opening at the lower portion thereof as at 15.

In the use of my device, the type is set in the regular way after which a mat 16 thereof is made. The mat 16 then has its intermediate portion placed within the concaved intermediate portion *a* of the female clamping member 7, with the opposite edges of the mat overlapping the side wings *b* as clearly suggested in Figure 2.

The plate 12 is then disposed against the mat 16 having the convex surface of its intermediate portion disposed against the intermediate portion of the mat 16, after which the pivotally mounted male member 8 is swung to that position shown in Figure 4 so that its

100

intermediate convex part is disposed oppositely the concave part 13 of the plate 12, as clearly suggested in Figures 3 and 4.

For retaining the parts in this clamped position, the pivotally mounted male member 8 on opposite edges thereof has pivoted thereto as at 17 one end of a swingable latch member designated generally by the reference character 18. Each latch member 18 comprises a shank having at its free end a handle 19, while intermediate its ends, the shank is provided with a lower projection 20 for engagement with a pin 21 projecting from a corresponding side of the stationary 15 female clamping member 7 for securing the said members in clamped position.

The male clamping member 8 adjacent the upper edge of its convex intermediate portion is provided with a transversely extending 20 opening or slot 22 through which hot molten metal is to be poured when the plate 12 and mat 16 are clamped between the members 7 and 8, from which sheet of metal the printing plate, as is obvious, is cast.

25 It is also to be noted that the plate 12 at its upper edge is provided with a handle 23 the metallic shank portion of which handle is curved transversely to provide as it were, a pouring spout, and this handle, as is obvious, 30 at the same time, will expedite the lifting of the plate from between the clamping members 7 and 8 whereby the plate, when removed, may be turned upside down to fall upon a table, after which it may be then quickly 35 placed in its former position for forming another printing plate.

As is apparent, plate 12 holds the printing mat in position within the clamp and that further the plate 12 provides as it were a tray 40 for lifting the mat from the clamp subsequent to the casting of the printing plate. Further, the size of the opening 15, controls the size of the printing face of the mat, since obviously, and as suggested in Figure 4, the 45 printing face of the mat is received within this opening 15.

It is also to be understood that this device is capable of use with or without an electrical heating element (not shown).

50 From the foregoing then, it will be seen that printing plates having a curved surface may be cast in a curved casting box of this character, in an inexpensive manner, with a minimum amount of time and that the plates 55 so cast will be of sufficient durability, strength, and otherwise embody the desired quality of such curved printing plates.

It is thought that from the foregoing description, taken in connection with the accompanying drawings, a clear understanding 60 of the operation, construction, utility and advantages of my invention will be had by those skilled in the art without a more detailed description.

65 It is to be understood that the invention

is not limited to the specific form as herein shown and described, but that the same is susceptible to changes in size, shape, and materials used, and other details of construction, as come within the spirit of the invention, and the scope of the appended claims. 70

Having thus described the invention, what I claim as new is:

1. In a casting box of the character described, a pair of clamping members, one of said members provided with a concaved portion adapted to accommodate the printing mat, an apertured plate adapted to be disposed against the printing mat, within said concaved portion, the other of said clamping members provided with a convex portion adapted to be disposed oppositely to said plate for accommodating between itself and the plate the molten metal, said first mentioned member at the lower edge of the concaved portion provided with a shoulder constituting a bottom for said concaved portion and the lower edge of said mat, apertured plate and the convex portion of the said clamping member being adapted for rest on 90 said shoulder.

2. In a casting box of the character described, a pair of clamping members, one of said members provided with a concaved portion adapted to accommodate the printing mat, an apertured plate adapted to be disposed against the printing mat, within said concaved portion, the other of said clamping members provided with a convex portion adapted to be disposed oppositely to said plate for accommodating between itself and the plate the molten metal, said first mentioned member at the lower edge of the concaved portion provided with a shoulder constituting a bottom for said concaved portion and the lower edge of said mat, apertured plate and the convex portion of the said clamping member being adapted for rest on 100 said shoulder, latch means for holding said clamping members in clamping relation and said second mentioned clamping member provided with an opening through which the molten metal may be poured between said second clamping member and said apertured plate. 110

3. A casting box of the character described comprising a pair of complementary clamping members, one of which is provided with a concaved portion and the other of which is provided with a convex portion complementary to the concaved portion, said one clamping member adapted to accommodate in the concaved portion thereof the printing mat, and a plate for disposition in said concaved portion intermediate the mat and the convex portion of said second clamping member, said plate being convex, and provided with an aperture for accommodating and regulating the size of the printing base of the mat, and said plate at the upper 120 125 130

end thereof provided with a handle having a concaved portion to provide a pouring spout for the casting box.

4. A casting box comprising a relatively fixed clamping member provided with a concaved intermediate portion and oppositely extending wings projecting therefrom, said member at the lower end of said concaved portion being provided with a shoulder, a printing mat arranged in the concaved portion and having opposite end portions overlapping said wings, a concaved plate adapted to fit within the concaved portion of said clamping member in contact with the printing mat, the said plate provided with an aperture for accommodating the printing surface of the mat, a second clamping member movable toward and away from the first clamping member, said second clamping portion provided with a convex portion constituting a projection for disposition opposite said concaved plate and adapted at its lower edge to rest on said shoulder, said second clamping member having wings projecting from opposite sides thereof for disposition opposite corresponding wings on the first mentioned clamping member, said second mentioned clamping member at the upper portion thereof provided with an opening through which molten metal may be poured, and said plate at the upper portion thereof provided with a handle having a concaved portion to provide a pouring spout, and means for clamping said clamping members in clamped relation.

In testimony whereof I affix my signature.
GEORGE A. STOFFEL.
